UNITED STATES PATENT OFFICE.

CHARLES J. CARLSTRAND, OF MINNEAPOLIS, MINNESOTA.

KNOCKDOWN CHRISTMAS TREE.

1,345,475.

Specification of Letters Patent.

Patented July 6, 1920.

Application filed June 9, 1919. Serial No. 302,732.

To all whom it may concern:

Be it known that I, CHARLES J. CARLSTRAND, a citizen of the United States, residing at Minneapolis, in the county of 5 Hennepin and State of Minnesota, have invented certain new and useful Improvements in Knockdown Christmas Trees; and I do hereby declare the following to be a full, clear, and exact description of the invention, 10 such as will enable others skilled in the art to which it appertains to make and use the same.

My invention has for its object to provide an artificial knock down Christmas tree 15 which is adapted to be chiefly made in planing mills, sash and door factory and elsewhere, where wooden articles are made.

This artificial knock down Christmas tree comprises a knock down tree, a base, a trunk 20 or column, a plurality of arms or so-called branches, and candle sticks applied to the ends of the branches or arms. These several parts are capable of being interlocked quickly to form a Christmas tree and to be 25 quickly separated, so that the elements of the Christmas tree may be packed away in small space for shipment or storage.

A Christmas tree of this character will have ornamental appearance and will last 30 indefinitely. It is made up of a plurality of wooden elements of the simplest kind of character which is therefore adapted to be very cheaply made, and moreover may be made of small or short pieces of lumber or 35 wood that are not useful for any other purpose and which therefore, have small commercial value.

In the accompanying drawings which 40 illustrate the invention, like characters indicate like parts throughout the several views.

Referring to the drawings:

Figure 1 is a perspective view of the 45 Christmas tree, showing candles applied thereto, one of the arms or branches being removed;

Fig. 2 is a perspective view some parts broken away, showing the base and a portion of the trunk of the tree, certain of the elements being separated to better illustrate 50 the manner in which they are adapted to be interlocked;

Fig. 3 is a fragmentary horizontal section approximately on the line 3—3 of Fig. 1; and

Fig. 4 is a fragmentary horizontal section 55 approximately on the line 4—4 of Fig. 1.

The base is made up of three elements to wit; a long flat piece bar 5 and two shorter bars 6. The bar 5 at the intermediate portion of the side is formed with 60 mortise 7, and to engage these mortises at end of the bar 6 is formed with tenons 8 that are adapted to closely fit mortises 7. Bar 5 at the central portion of its front is provided with a mortise 9 that is adapted 65 to be engaged by the tenon 10 of the trunk 11. The trunk 11 is preferably a rectangular wooden bar, the upper end of which is reduced at 12 and formed with an axial hole that is adapted to hold a candle a. In its 70 flat side the trunk 11 is formed at different vertical points with mortise 13 that are adapted to receive the tenons 14 of arms or branches 15. At certain places the corners of the trunk 11 are provided with mortises 75 17 that are adapted to be engaged by tenons 18 and on inner end members 19.

It will be noted that the branches 15 are sets of four with the members of the set in 80 the same horizontal plane, and that the branches 19 are also in sets of four with the members of the same horizontal plane, but that the set of arms 15 and 19 are in different horizontal planes so that the arms are distributed evenly and project from the tree 85 in such manner as will give a good imitation of an actual tree. The said arms or branches from the direction from the bottom toward the top are progressively shorter and shorter so as to further imitate a tree. 90

To the outer ends of the branches or arms 15 and 19 are applied candle sticks or 95 holders 20. These holders or candle sticks 20 are preferably square wooden blocks suitably secured through the outer ends of the branches and having holes adapting them to receive candles a'.

The members that make up the tree may be painted in any desired color, but preferably would be painted green to further indicate a Christmas tree. A tree of the above character in actual practice has been found to be extremely useful for the purpose had in view. It is very strong and may be loaded with all sorts of ornamental articles as well 100 as the Christmas presents. It may be set up quickly for use and knocked down more quickly when time of use is over. More- 105

over, it will last many years so that its total cost is very small. Of course, it may be made in all sorts of fashions.

What I claim is:

- 5 An artificial knock down Christmas tree comprising a base made up of interlocked members, a trunk that is square in cross section and is provided at its lower ends with a tenon adapted to fit a mortise in one
- 10 of the base members, said trunk at different vertical points having horizontal groups of mortises in its flat sides, said trunk further having its corner edges provided with mor-

tises arranged in horizontal groups between said first groups, arms or branch members 15 having tenons on their inner ends for interlocking engagement with the mortises above noted in said trunk, block like candle sticks applied to the outer ends of said branches or arms.

20 In testimony whereof I affix my signature in presence of two witnesses.

CHARLES J. CARLSTRAND.

Witnesses:

CLARA DEMAREST,
BERNICE G. BAUMANN.
